UNITED STATES PATENT OFFICE

JOSEPH B. STRAUSS, OF CHICAGO, ILLINOIS

LIFEBOAT SYSTEM

Application filed January 8, 1930. Serial No. 419,238.

This invention relates to life boat systems and has for its object to provide a new and improved system of this description. The ordinary life boat arrangement at present is to have the life boat on the deck of the vessel and to then lower the boat into the water at the side of the vessel when it becomes necessary to use the life boat. In stormy water this is a difficult process and often results in the loss of life.

My present invention has as one of its objects to provide a life boat system which will avoid these difficulties and by means of which passengers on a large vessel can be easily and quickly loaded onto the boats and the boats released without delay and without danger to the passengers.

The invention has as a further object to provide life boats which shall be kept in recesses in the side of the vessel when not in use and which can easily and quickly be filled with passengers.

The invention has further objects which are more particularly pointed out in the accompanying description.

Referring now to the drawings, Fig. 1 is a side elevation of a ship showing the life boat in position in a recess therein.

Fig. 2 is an end view of the vessel shown in Fig. 1 with parts broken away to show the life boat.

Fig. 3 is a view similar to Fig. 2 showing the life boat released.

Fig. 4 is a side view of the vessel with parts broken away showing the means of access to the life boat from the exterior of the vessel.

Fig. 5 is an enlarged side view of the vessel with parts broken away showing the life boat in position in the recess and the surrounding construction.

Fig. 6 is a sectional view on line 6—6 of Fig. 1.

Fig. 7 is an enlarged sectional view with parts broken away on line 7—7 of Fig. 1.

Fig. 8 is a vertical sectional view taken on line 8—8 of Fig. 5.

Fig. 9 is a view similar to Fig. 8 showing the life boat fastening mechanism released.

Fig. 10 is a sectional view taken on line 10—10 of Fig. 5.

Fig. 11 is an enlarged sectional view through the controlling mechanism for the door at the side of the vessel which closes the recess containing the life boat.

Fig. 12 is a view similar to Fig. 11 with parts omitted and showing the mechanism in a different position.

Fig. 13 is a sectional view taken on line 13—13 of Fig. 11.

Like numerals refer to like parts throughout the several figures.

Referring now to the drawings, I have shown a vessel which may be of any suitable description such as a large passenger vessel.

This vessel is provided at its side with one or more recesses 2. Each recess contains a life boat 3. Since the recesses and life boats are all similar, I have only shown one for purposes of illustration.

These life boats may be of any suitable size but when used with large vessels are preferably large boats operated by their own power. If only one life boat is used, it may be large enough to seat all the people on the vessel.

If desired, one or more of these life boats may be placed on each side of the vessel and in that event they may be smaller, if desired. When a number of these life boats are used, they should be of such size as to seat all the passengers and the crew, the purpose of the system being to provide in one, two or more life boats an arrangement for all the passengers and crew so that the entire ship load can be easily and quickly and safely removed from the vessel. The life boats when not in use, ride upon the water within the recesses in the side of the vessel and are detachably connected so that they may be instantly released.

85

90

These boats are preferably non-sinkable with closed tops, wireless instruments and the like so that when released they are independent of the vessel and under full control. One or 5 more officers of the vessel may be delegated for a permanent station on each life boat. There is a door for the recess in which each each life boat is received which conforms to the exterior of the vessel so that the appearance 10 of the vessel is not altered. Means may be provided for loading the life boats from within the vessel or by means of ladders or the like from the exterior of the vessel. The recess in the vessel is of such height that 15 when the life boat is therein, it will ride upon the water so that when released all that must be done is to move it laterally out of the recess.

Referring now to Figs. 8, 9 and 10, where- 20 in I have shown one form of construction embodying the invention, the recess 2 is provided with a door 4, which is normally closed and which conforms to the contour of the exterior of the vessel. The inner wall 5 of the 25 recess 2 is, of course, water tight. Some means is provided for holding this door closed and for quickly opening it and moving it out of the way of the life boat so that the life boat may be quickly launched.

30 In the drawings I have illustrated one mechanism for this purpose. In this construction the door is pivotally connected with a carriage 6 by means of the pivot 7. This carriage is mounted between the guides 8 and 35 9 and is provided with rollers 10 which run along these guides. (See Figs. 7 and 8.) The carriage 6 carrying the door with it is run back and forth along the guides by some suitable mechanism. As herein shown the carriage 40 has connected with it a rack 11 which is engaged by a pinion 12 on a shaft 13. A sleeve 14 surrounds the shaft 13 and is provided with a worm 15 engaged by a worm gear 16 on a shaft 17. Associated with a 45 shaft 13 is a clutch member 18 feathered to the shaft and which engages a clutch member 19 on the sleeve 14.

The clutch member 18 is controlled by the 50 forked member 20. A cam 21 is connected with the shaft 17 and is provided with a cam face 22 which at the proper time engages the member 20 so as to move the clutch member 18 to disconnect it from the clutch member 19. A spring 23 retracts the member 20 55 when the cam face 22 is not engaging it so as to move the clutch member 18 into engagement with the clutch member 19. The cam 21 is also provided with a cam slot 24 in which works a projection 25 on the arm 26. 60 This arm has connected with it a member 27 which is attached to a crank 28 on a shaft 29. (See Figs. 10, 12, and 13.) This shaft is provided with a holding piece 30 having a groove 31 in which is received the end 32 of 65 the door 4, as clearly shown in Fig. 8. When

the shaft 17 is rotated, the cam 21 causes the arm 26 to be moved downwardly so as to rotate the shaft 21 to release the bottom of the door 4. The door is then moved laterally out of the way of the life boat by rotating 70 the shaft 13, the gear 12 moving the rack 11 and carriage 6 along the guides 9 and 10 to the position shown in Fig. 5 and in dotted lines in Figs. 6 and 7. The shaft may be rotated by a suitable motor. Means is also provided for rotating this shaft on the outside 75 of the vessel. This is accomplished by means of the hand wheel 33 on the shaft 34 which has a spindle wheel 35 over which passes a belt 36 which also passes over a spindle wheel 80 37 on the shaft 13. (See Fig. 10).

Some means is provided for holding the life boat 3 in position while in the recess 2. As herein shown this is accomplished by the holding devices 38 at each end of the life boat. 85 These holding devices have arms which hook over projections 39. The arms are pivoted at 40 and have racks 41 which engage pinions 42 on the shaft 43 which extends across from one end of the life boat to the other, as clearly 90 shown in Fig. 5. The shaft 43 is rotated in any suitable manner as by means of a hand wheel 44 connected with a shaft 45 having thereon a worm 46 which engages a worm wheel 47 on the shaft. This shaft may be also 95 rotated from within the life boat by the hand wheel 46a.

By rotating the shaft 43, it will be seen that the holding device 37 may be lifted to dis- 100 engage the projections 39 and release the life boat. The door 4 may be opened from within the life boat by means of a hand wheel 48 which actuates a shaft 49 with which is connected a belt 50, the belt being connected with the shaft 13 so that when the hand wheel 48 105 is turned, the shaft 13 will be rotated and the holding device 30 released and the door 4 moved out of the way. Access from the interior of the vessel to the life boat is secured through the hatchway 51. (Fig. 7.) Some means is provided for resiliently holding the life boat in its recess so it will not be knocked about to become injured and this means must be easily releasable.

In the construction shown, this result is se- 115 cured by providing a series of spring pressed rollers 52. The life boat may be engaged by the spring pressed rollers 56 which are connected by springs 57 with the top of the recess 2. Access to the life boat may be had from the 120 exterior of the vessel by means of the ladders 58 and 59 which are pivotally suspended near the deck and which can be lowered, as illustrated in Fig. 5 so that the passengers can pass down into the life boat. I have shown 125 the life boat as being provided with a propeller 60 and a rudder 61. The propeller is driven by any suitable power agency located within the life boat. The recess in the ship has a portion above and a portion below the 130

water line and in Figures 8, 9, and 10 I have shown the water line by the line 62.

The use and operation of my invention is as follows.

Under normal conditions, the life boats are within the recesses 2 and the doors 4 are closed; as shown in Figs. 1, 2, 8, and 10. When it is desired to use the life boats, the passengers may be delivered thereto from the interior of the vessel through the hatchways 51. When the boat is ready to be released, the hand wheel 44 or 46a may be rotated so as to move the holding devices 38 to release them from the projections 39. The door 4 may then be opened by turning the hand wheel 33 which actuates the shaft 49 and belt 50 which is connected with sleeve 14 so as to drive it. This first releases the bottom of the door by rotating the cam 21 so as to cause the projection 25 and the member 26 to be moved upwardly so that the part 27 causes the shaft 29 to rotate to move the holding piece 30 to disconnect the bottom of the door, as shown in Fig. 9. When the door is properly disconnected, the high part 22 of the cam 21 becomes disengaged from the member 20 and the spring 23 moves said member so as to engage clutch members 18 and 19 (Fig. 11). The further movement of the hand wheel 33 then rotates shaft 13 and pinion 12 and by means of rack 11 moves the carriage 6 laterally along its guides 9 and 10 thus carrying the door 4 to the left, as shown in Fig. 5 and in dotted lines in Figs. 6 and 7. This moves the door to one side of the recess so that the life boat 3 which is riding upon the water, is free to move out away from the vessel. If it becomes desirable to have the passengers enter the life boat by means of the ladders 58 and 59, the door 4 is first moved to one side and this may be accomplished by turning the hand wheel 33 on the exterior of the vessel. This, by means of shaft 34 and belt 36 rotates the sleeve 14 on the shaft 13 so as to rotate cam 21 in the same manner as is done by turning the hand wheel 48. The ladders 58 and 59 are then lowered, as shown in Fig. 5 and the passengers admitted to the life boat through the openings 55. The boat then is released by turning the hand wheel 46a which moves the holding devices 38 and disconnects them from the projections 39. The boat is then driven by its own power away from the vessel to a point of safety. It will be seen that by means of this system, large life boats may be used which will hold a large number of people and which can be driven by its own power safely, through rough seas. It will further be seen that these life boats can be easily and quickly and safely launched or operated from the main vessel and this can be done regardless of stormy conditions or high waves or the like.

I claim:—

1. In a life boat system, a ship, a power

boat associated therewith, said ship being provided with a recess in its side at the water line, said boat located in said recess and normally in the water within said recess, the outer face of the lift boat when in said recess being within the boundaries of said ship. 70

2. In a life boat system, a ship, a power boat associated therewith, said ship having a recess in its side at the water line, said boat riding the water within said recess, a holding device for holding the boat within said recess, the outer face of the life boat when in said recess being within the boundaries of said ship when not in service, releasing mechanism connected with said holding device for releasing the life boat while it is floating in the water, said releasing mechanism controlled from the ship whereby the boat may be quickly detached for operation independently of the ship. 80

3. In a life boat system, a ship, a power boat associated therewith, said ship having a recess in its side at the water line, said boat riding the water within the said recess, the outer face of the life boat when in said recess being within the boundaries of said ship, a holding device for holding the boat within said recess when not in service, releasing mechanism connected with said holding device for releasing the life boat while it is floating in the water, said releasing device controlled from the ship and from the boat whereby the boat may be quickly detached for operation independently of the ship. 90

4. In a life boat system, a ship, a power boat associated therewith, said ship provided with a recess in its side at the water line, said boat riding the water within said recess and a cover over said recess to enclose said boat when not in service. 100

5. In a life boat system, a ship, a power boat associated therewith, said ship having a recess in its side at the water line, said boat riding the water within said recess and a cover over said recess to enclose said boat when not in service, and means for automatically releasing said cover with the release of the boat. 110

6. In a life boat system, a ship, a power boat associated therewith, said ship having a recess in its side a portion of which extends above and a portion below the water line, said boat riding the water within said recess so as to be free to float out away from the ship when released, a ladder pivoted to the ship near the deck and adapted to be moved to permit access to said boat from the deck. 115

7. In a life boat system, a ship, a power boat associated therewith, said ship having a recess in its side at the water line, said boat riding the water within said recess, a cover over said recess to enclose said boat, said cover, when in its closed position, being in the plane of the side of the ship. 120

8. A life boat system comprising a ship 130

provided with a recess which has a portion extending below the water line and a portion extending above the water line, a life boat in said recess, a door for said recess which has an outer surface which corresponds with the outer surface of the ship.

9. A life boat system comprising a ship provided with a recess which has a portion extending below the water line and a portion 10 extending above the water line, a life boat in said recess, a door for said recess, holding means for holding said door in position and a releasing device for releasing said door.

10. A life boat system comprising a ship 15 provided with a recess which has a portion extending below the water line and a portion extending above the water line, a life boat in said recess, a door for said recess, holding means for holding said door in position, a 20 releasing device for releasing said door and a carriage upon which said door is supported when released so that it may be moved to one side to free the boat.

11. A life boat system comprising a ship 25 provided with a recess which has a portion extending below the water line and a portion extending above the water line, a life boat in said recess, a door for said recess, holding devices at each end of the boat for holding 30 it in position and means for releasing said holding devices.

12. A life boat system comprising a ship provided with a recess which has a portion extending below the water line and a portion 35 extending above the water line, a life boat in said recess, a door for said recess, holding devices at each end of the boat for holding it in position, means for releasing said holding devices, and cushioning means interposed 40 between the boat and the wall of the recess.

13. A life boat system comprising a ship, provided with a recess at its side part of which is below the water line, a life boat in said recess, a door for the recess for protecting the life boat, a fastening device for holding said door and means operable from either within or without the ship for operating said fastening device.

14. A life boat system comprising a ship 50 provided with a recess at its side part of which is below the water line, a life boat in said recess, a door for the recess for protecting the life boat, a fastening device for holding said door, means operable from either 55 within or without the ship for operating said fastening device, a movable carriage upon which said door is supported and means for moving said carriage laterally to open or close the door.

15. A life boat system comprising a ship provided with a recess at its side part of which is below the water line, a life boat in said recess, a door for the recess for protecting the life boat, a fastening device for holding 60 said door, means operable from either

within or without the ship for operating said fastening device, a movable carriage upon which said door is supported, means for moving said carriage laterally to open or close the door, and said means operable either from within or without the ship.

Signed at Chicago county of Cook and State of Illinois, this 21st day of December 1929.
